UNITED STATES PATENT OFFICE.

JAMES L. KIMBALL, OF VIRGINIA, MINNESOTA.

STEEL TIE.

1,271,040.

Specification of Letters Patent.

Patented July 2, 1918.

Application filed March 1, 1916. Serial No. 219,878.

To all whom it may concern:

Be it known that I, JAMES L. KIMBALL, a citizen of the United States, residing at Virginia, in the county of St. Louis and State of Minnesota, have invented certain new and useful Improvements in Steel Ties; and I do declare the following to be a full, clear, and exact description of the invention, such as will enable others skilled in the art 10 to which it appertains to make and use the same.

This invention relates to railway ties, and it relates more particularly to certain improvements on my railway ties which constitute the subject-matter of my Patents No. 993,254, granted May 24, 1911, and No. 1,013,023, granted December 26, 1911.

One of the objects of my invention is to generally improve and cheapen the construction of railway ties of this character.

Another object is to provide a combined steel and concrete tie which is thoroughly practical, efficient, and substantially indestructible.

25 Another object of this invention is to provide a railway tie of this character which is more resilient than other similar constructions.

Another object is to provide a thoroughly efficient securing means for the spikes which hold the railway rails on the seats of the ties.

Another object is to provide securing means of this character from which the spikes may be quickly and easily disengaged 35 when desired.

Another object is to provide means whereby the railway spikes may be duplicated in connection with the securing means, in such relation that the spike which is engaged by 40 the securing means serves as a means for securing the adjacent spike in its operative position.

Another object is to provide a substantial metal backing for the railway spikes, said 45 backing being supported by the cement filling, which latter also supports the rail seat.

Other objects and advantages may become apparent to persons who read the following details of description in connection 50 with the accompanying drawings, in which:

Figure 1 is a top, plan view of my improved railway tie having fragments of railway rails seated and secured thereon;

Fig. 2 is a vertical, sectional view taken 55 along the line of 2—2 of Fig. 1;

Fig. 3 is a transverse, vertical, sectional view taken along the line of 3—3 of Fig. 1;

Fig. 4 is a longitudinal, vertical, sectional view taken along the line of 4—4 of Fig. 1;

Fig. 5 is a perspective view of the sheet 60 steel cap of the tie;

Fig. 6 is a perspective view illustrating the three separate concrete blocks which constitute the base and filler of the tie;

Fig. 7 is a fragmental top, plan view illustrating the tie employing pairs of spikes for engagement with each side of the rail base; 65

Fig. 8 is a transverse vertical, sectional view along the line of 8—8 of Fig. 7. 70

Referring to these drawings in detail, in which similar reference characters correspond with similar parts throughout the several views, the rails A and spikes B may be of ordinary construction, and are not described in detail. The railway tie consists mainly of the elements illustrated separately in Figs. 5 and 6, the first of these elements or members 10 consisting of a channel beam of steel or other sheet metal which is preferably more or less springy. Each of the members 10 is provided with slits 11 and 12, and with relatively long and narrow openings 13, each of which communicates with a pair of the slits 11 and 12 in such manner as 85 to provide springs or tongues 14. The extreme end 16 of each tongue is spaced from the opposing wall of the opening 13 a distance somewhat less than the thickness of an ordinary railway spike, so that when the 90 spike is driven into the opening 13 at the part opposite the tongue 14, this operation forces the tongue into the position shown in Fig. 2, it being understood that suitable backing, hereinafter described, cooperates 95 with the spike for thus deflecting the tongue or spike-engaging spring 14. The openings 13 are considerably longer than the width of the shank of an ordinary railway spike, and the width of each tongue 14 is substantially 100 equal to the width of an ordinary railway spike. Each tongue 14 extends substantially from side to side of the rail seat, so that the rail acts as a guard for preventing the tongues from being disengaged from the respective spikes. The openings 13 extend substantially at right angles to the respective tongues 14, and when it is desired to disengage the tongues from the spikes the latter may be forced in their lateral direction, in 110

the longitudinal direction of the openings 13, and thereby disengaging the spikes from the respective tongues 14, and the spikes may be easily withdrawn from said openings. 5 By referring to Fig. 1, in which the slits 11 and 12 are shown in dotted lines under the rails A, it will be seen that the pair of tongues at each end of the tie extends in opposite directions. In other words, the 10 openings 13 being on opposite sides of the rail A, it is necessary that the tongues 14 extend in opposite directions in order to communicate with the spike-receiving openings at the opposite sides of the rail A, in 15 view of the said tongues being positioned under the rail.

The sheet metal element 10 is stiffened and kept straight by means of the down-turned flanges or walls 17, and the latter 20 are provided with apertures 18 for a purpose hereinafter set forth.

The combined base and filler shown in Fig. 6 is preferably formed in three parts 19 and 20, the two end parts being of substantially 25 counterpart and interchangeable construction. These parts 19 and 20 are separately constructed in order that they may be interchanged or replaced by similar ones in case one of them should become 30 damaged. Only one of the members 19 will be described, and this description will suffice for the other. Each member 19 is of a size and shape to fill the space between the flanges 17, at one end of the member 10, 35 apertures 21 being provided in position to be alined with the apertures 18, so that bolts or other securing members 22 may be extended therethrough for securing the metal and concrete members together as a 40 unitary structure. Each member 19 is preferably broadened by the provision of flanges 23 which extend laterally beyond the lower edges of the flanges 17, and provide a relatively 45 wide base, so that the tie may have a broad foundation, while having a comparatively narrow top or cap, thus minimizing the expense by reducing the size of the more expensive of the elements which enter into the construction.

50 Each of the cement blocks or members 19 is provided with depressed portions 24, adapted to receive the respective springs 14, and communicating with each depression is a vertical aperture 25 adapted to 55 receive one or more spikes B. The apertures 25 preferably extend entirely through the member 19 and register with the respective openings 13 of the member 10. In order that the wall of the aperture 25 will 60 not crumble or wear away under the pressure of the spike or spikes, a metal plate 26 is provided. The plate 26 is preferably formed with flanges 27 which extend into the body of the concrete element 19 and 65 securely hold the plate 26 in position.

In order that the concrete blocks may be held intact even if they should become broken, I provide reinforcing rods 28 and 29, which are preferably C-shaped, although their free ends may be brought into contact with one another, and in either event the rods 28 and 29 form substantially rectangular, open frames, which extend approximately from end to end of the blocks and surround the apertures through which 75 the bolts 22 extend.

From the foregoing description, it will be seen that I have provided a very simple and yet very complete and practical railway tie which should meet with great favor 80 and commercial success.

Referring now to Figs. 7 and 8, it is here shown how the spreading of the rails may be effectually prevented by doubling the resistance to the spreading of the rails. In 85 these views, especially in Fig. 8, it is shown that two spikes B may be placed side by side within one of the apertures or openings 13, and the corresponding opening 25. When thus placed within the openings 13 and 25, 90 one of the spikes is first placed in the part of the opening away from the end of the detent or spring 14 and the other spike is then driven into the openings 13 and 25 in such position that one of its vertical sides 95 is engaged between the adjacent tongue or detent 14 and the backing plate 26, and the head of this latter spike extends over the head of the adjacent spike, as illustrated in Fig. 8, so that both of the spikes B are 100 effectually detained or locked in the openings 13 and 25, and can only be removed therefrom by the application of sufficient force against the overlapping spike head to force it away from or past the other spike 105 head, whereupon the innermost spike may be easily drawn from the apertures 13 and 25, and the other spike may then be removed by forcing it laterally away from the detent 14.

110 Although I have described this embodiment of my invention very minutely, it is to be understood that my invention is not limited by these exact details of construction and arrangement of parts, but I am 115 entitled to make such minor changes that do not constitute a departure from the inventive idea expressed in the foregoing description and following claims:

What I claim as my invention is—

120 1. In a railway tie, a sheet metal element formed integrally with a struck-up spike-engaging tongue and having a spike-receiving opening at the free end of said tongue, and a concrete block coöperative with the extreme free end of said tongue for locking a spike in said opening.

125 2. In a railway tie, a sheet metal element formed integrally with a struck-up spike-engaging tongue and having a spike-receiving opening at the free end of said tongue, and a concrete block coöperative with the extreme free end of said tongue for locking a spike in said opening.

130

ing opening at the free end of said tongue, a metal element coöperative with the extreme end of said tongue for locking a spike in said opening, and a concrete block securing the second said metal element in fixed relation to the first said metal element and supporting the latter.

3. In a railway tie, a sheet metal element formed integrally with a struck-up spike-engaging tongue and having a spike-receiving opening at the free end of said tongue, and means coöperative with the extreme free end of said tongue for locking a spike in said opening, said opening having a portion offset from the end of said tongue and being adapted to receive a spike out of engagement with said tongue, for the purpose specified.

4. In a railway tie, a metal element provided with an opening and with slits extending respectively from one end and from the middle part of said opening so as to form a spike-engaging tongue having its free end disposed at only one side of said opening, said opening being considerably wider than the shank of an ordinary railway spike, whereby a spike may be moved laterally out of engagement with said tongue.

5. In a railway tie, the combination of a metal element provided with a spike-receiving opening which is considerably longer than the width of the shank of an ordinary railway spike, and a flat spring of a width considerably less than the length of said opening and supported at right angles to said spike-receiving opening and in position to engage its extreme end with a spike when the latter is in one end of the opening,

said spring being out of engagement with the spike when the spike is in the other end of said opening.

6. In a railway tie, the combination of a metal element provided with a spike-receiving opening which is considerably longer than the width of the shank of an ordinary railway spike, a flat spring of a width considerably less than the length of said opening and supported at right angles to said spike-receiving opening and in position to engage its extreme end with a spike when the latter is in one end of the opening, said spring being out of engagement with the spike when the spike is in the other end of said opening, and a metal element supported in fixed relation to the first said metal element and being coöperative with said spring for securely holding a spike against outward longitudinal movement.

7. In a railway tie, a sheet metal element comprising a rail-seat provided with slits extending longitudinally of the tie, said plate being provided with an opening communicating with said slits so as to provide a tongue in a position to be covered by a rail when the latter is on said rail-seat, whereby said tongue is guarded by the rail, and guarded means coöperative with said tongue for securing a railway spike in said opening.

In testimony whereof I have hereunto set my hand in the presence of two subscribing witnesses.

JAMES L. KIMBALL.
